United States Patent Office

Des. 182,945

Patented June 3, 1958

182,945

HIGHWAY MARKER FOR WET TRAFFIC LINES

James Back, Dayton, Ohio, assignor of one-half to
John C. Weigel, Dayton, Ohio

Application January 7, 1957, Serial No. 44,411

Term of patent 14 years

(Cl. D72—1)

Fig. 4

Fig. 1 is a view in perspective of a highway marker for wet traffic lines, showing my new design;

Fig. 2 is a front elevational view, thereof, the rear being substantially plain;

Fig. 3 is a right side elevational view of Fig. 2; and

Fig. 4 is a bottom plan view of Fig. 2 in an inverted position.

I claim:

The ornamental design for a highway marker for wet traffic lines, as shown and described.
